CLAIM

The ornamental design for a set of toy robot arms, as shown and described.

DESCRIPTION

The present application is related to U.S. Design patent application Ser. No. 29/576,971, entitled “Toy Robot Body”, filed concurrently herewith, and to U.S. Design patent application Ser. No. 29/576,972, entitled “Toy Robot Body”, filed concurrently herewith, and to U.S. Design patent application Ser. No. 29/576,973, entitled “Toy Robot Head”, filed concurrently herewith, and to U.S. Design patent application Ser. No. 29/576,974, entitled “Toy Robot Head”, filed concurrently herewith, and to U.S. Design patent application Ser. No. 29/576,976, entitled “Toy Robot Eye”, filed concurrently herewith, and to U.S. Design patent application Ser. No. 29/576,976, entitled “Toy Robot Eyes”, filed concurrently herewith, and to U.S. Design patent application Ser. No. 29/576,983, entitled “Set of Toy Robot Arms”, filed concurrently herewith, and to U.S. Design patent application Ser. No. 29/576,991, entitled “Set of Toy Robot Arms”, filed concurrently herewith, the entire disclosures all of which are incorporated herein by reference.

FIG. 1 is a front perspective view of a set of toy robot arms according to our design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines illustrate unclaimed environmental structure and form no part of the claimed design.
